UNITED STATES PATENT OFFICE.

ROBERT T. PARISEN, OF KNOXVILLE, PENNSYLVANIA, ASSIGNEE TO LAWSON MANUFACTURING COMPANY, OF HOMESTEAD, PENNSYLVANIA, A CORPORATION OF PENNSYLVANIA.

THERMOSTATIC VALVE.

1,102,070.

Specification of Letters Patent. Patented June 30, 1914.

Application filed January 23, 1914. Serial No. 813,902.

To all whom it may concern:

Be it known that I, ROBERT T. PARISEN, a citizen of the United States, and resident of Knoxville, in the county of Allegheny and State of Pennsylvania, have invented certain new and useful Improvements in Thermostatic Valves, of which the following is a specification.

This invention relates to thermostatic valves, and particularly to valves of the general type illustrated in patent granted to me October 14, 1913, No. 1,075,934, such valves being designed primarily for automatically controlling the flow of gas for heating stand boilers, etc.

The primary object is to improve and simplify the construction, with the several parts so arranged as to apply the operating forces directly and without straining or cramping tendency.

Another object is to render the working parts readily accessible; also to adapt the valve to the hand adjustment disclosed in patent to Lindley S. Lawson, No. 1,038,159, September 10, 1912.

In the accompanying drawings, Figure 1 is a longitudinal section of a valve mechanism embodying the invention, a portion thereof being shown in elevation. Fig. 2 is a longitudinal section taken at right angles to Fig. 1. Figs. 3 and 4 are cross sections taken on lines 3-3 and 4-4, respectively, of Fig. 1.

Referring to the drawings, 2 designates the valve casing having the diametrically opposite inlet and outlet ports 3 and 4, respectively. The casing is of general cylindrical form with an open side or end 2' closed by the screw closure or plug 5. At its opposite side the casing is contracted to form the tubular threaded extension 6 which is adapted to be secured in the wall of a stand boiler or other water container. A thermostatic tube 7 is secured in the extremity of extension 6 and incloses the neutral thermostatic rod element 8.

The opposite transverse walls 9 and 10 within casing 2 form therebetween a depression or cavity 11 which at one end is open toward closure 5, and at its opposite end communicates with the hollow interior 6' of the casing extension 6. The portion of cavity 11 in the plane of ports 3 and 4 is

rounded or enlarged centrally at 11' and secured therein is the cup-like holder 12, 55 with inlet port 3 in open communication with one side thereof through wall 9, as indicated at 3'. The open end of holder 12 facing end 2' of the casing is closed by the plug-like valve seat 13, ported at 13'. A 60 valve 14 is confined within holder 12 and is adapted to be moved toward closed position by coiled spring 15. A stem 14' projects from the valve through a central aperture in seat 13, and this stem, together with 65 a similar stem 15' and guide 15" at the opposite face of the valve, maintain the valve in proper position and insure accurate movement thereof.

For transmitting movement from the 70 thermostat to the spring-closed valve 14 a forked support 16 is fitted and movable in cavity 11, the central stem-like portion 17 of the support fitting cavity 6' of the casing extension 6. The opposite side arms 18 of 75 the support embrace the valve holder 12, being movable in the side extensions 11' of cavity 11. Stem 17 is hollow and confined therein is spring 19 which bears against the closed end of valve holder 12 80 and opposes movement of the support 16 imparted thereto by the thermostatic element 8.

The coöperating movement-compounding levers 20 are fulcrumed to the opposite support arms 18 with the innermost lever engaging valve stem 14'. An adjustable abutment for the outermost lever consists of the stem 21 which is threaded through a central aperture in the casing cap 5, and at its 90 inner extremity provided with the lever-engaging steel bearing point 21'. Secured to stem 21 by nut 22 is a cap 23 which embraces and is rotatable relatively to the casing end 2', said cap thus comprising a hand-hold for adjusting the stem 21 to the temperature which the valve is to maintain, for this purpose the cap being provided with a pointer 24 which coöperates with a scale 95 25 on casing 2, as in the above mentioned 100 Patent No. 1,028,159.

The parts are assembled by first introducing support 16 into the casing cavity 11 and its side extensions 11'', and then with spring 19 in place in the support stem 17 105 the cup-like valve holder 12 is inserted in

the rounded portion 11' of the casing cavity, compressing spring 19, and being braced or soldered to walls 9 and 16 with its side post 3' in register with the casing inlet port 3. Levers 20 are then turned into operative relation and closure 5 is inserted, whereupon the levers may be placed under proper tension by adjusting the abutment forming stem 21, as above described. With neutral rod 8 inclosed in expansion tube 7, the latter is secured to the casing extension 4 with the rod bearing against support stem 17.

The valve as a whole is designed to regulate the flow of gas to a burner, for instance the burner of a boiler header, and the thermistor is subjected to the burner projected heat, the present adaptation casing extension 4 being entered in the wall of a boiler with the thermistor projected therein into and responding to temperature variations of the water. When the temperature drops below that at which the valve is set the contraction of thermometric tube 7 causes the neutral rod 8 to exert pressure on said move lever support 11 in opposition to position 16, and this very slight movement here compounded by levers 20 as to open valve 1 to the flow of an increased amount of gas to the burner, such increased flow continuing until the required temperature in the boiler is restored. If the valve is set adjusted so to constantly or under normal conditions pass seven gms in the burner, it will be anticipated that the operation just described results in still further opening the valve and thereby increasing the flow. The mechanism is capable of such accurate adjustment that if, for instance as illustrated in Fig. 1, it is set to maintain the water at 130°, that temperature will be maintained under ordinary working conditions, and will never be exceeded.

It is characteristic of the invention, that the operating forces are applied centrally or axially to the several working parts, thus precluding straining or cramping tendencies. Upon removing cap 23 and closure 5, the internal parts are readily accessible for replacements or repair.

Claims:-

1. The combination of a valve casing, a valve and a valve seat therein, a support within the casing and movable longitudinally of the valve axis and having parts between which the valve is located, operating levers fulcrumed to said parts with one of the levers adapted to transmit movement to the valve, an abutment for another of said levers, and a thermostatic device connected to the support for transmitting movement thereto.

2. The combination of a valve casing, a valve and a valve seat therein, reversely extending operating levers fulcrumed at opposite sides of the axial line of the valve with

one of said levers adapted to transmit movement to the valve, an abutment for another of said levers, a support for said levers within the casing and movable longitudinally of the valve axis, and a thermostatic device operatively connected to the support.

3. The combination of a valve casing, a valve and a valve seat therein, a lever support within the casing and movable in the direction of movement of the valve and having lever supporting arms at opposite sides of the valve, reversely extending operating levers within the casing and fulcrumed to the arms with one of said levers adapted to transmit movement to the valve, so as to abutment for another of said levers, and a thermostatic device operatively connected to the lever support.

4. The combination of a valve casing, a valve and a valve seat therein, the casing as formed with a hollow guide, a lever support within the casing and movable in the direction of movement of the valve and having a guiding extension fitting the hollow guide of the casing, a thermostatic device operatively connected to the support extending for transmitting movement to the support, operating levers within the casing and fulcrumed to the support with one lever adapted to transmit movement to the valve, and so abutment for another of said levers.

5. The combination of a valve casing, a valve and a valve seat therein, a lever support within the casing and movable in the direction of movement of the valve, a thermostatic device for imparting movement to the support, operating motion-compounding levers fulcrumed within the casing and to the support with one of said levers adapted to transmit movement to the valve, and so abutment for another of said levers.

6. The combination of a valve casing, a valve and a valve seat therein, a lever support movable in the direction of movement of the valve, a thermostatic device for imparting movement to the support in one direction, a spring for acting on the support to oppose the thermostatic movement, operating motion-compounding levers fulcrumed to the support with one of said levers adapted to transmit movement to the valve and an abutment for another of said levers.

7. The combination of a valve casing, a valve and a valve seat therein, a lever support movable in the casing and having a hollow guide forming extension, the casing having a hollow part in which said extension moves, a thermostatic device engaging the carrier extension for imparting motion in one direction to the carrier, a spring within the carrier extension for opposing the thermostatic movement, operating motion-compounding levers fulcrumed to the support with one of said levers adapted to

transmit movement to the valve, and an abutment for another of said levers.

8. The combination of a valve casing having inlet and outlet ports, the casing interior formed with a cavity with which one of the ports communicates, a valve seat and a valve within the cavity for controlling communication between the casing ports, co-operating-motion-compounding levers with one of said levers adapted to transmit movement to the valve, an abutment for another of said levers, a thermostatic device operatively connected to the levers for causing them to move the valve, and spring means for opposing such lever movement.

9. The combination of a valve casing having inlet and outlet ports, the casing interior formed with a cavity with which one of the ports communicates, a ported valve seat fitting the cavity and controlling communication between the inlet and outlet ports of the casing, motion-compounding levers with one of the levers adapted to transmit opening movement to the valve, an abutment for another of said levers, and a thermostatic device operatively connected to the levers for causing them to move the valve.

10. The combination of a valve casing having inlet and outlet ports, the casing interior formed with a cavity, a cup-like holder secured in the cavity and open to one of the casing ports, a seat carried by said holder, a spring-closed valve for the seat located within the holder, motion-compounding levers with one of the levers adapted to transmit opening movement to the valve, an abutment for another of said levers, and a thermostatic device operatively connected to the levers for causing them to move the valve.

11. The combination of a valve casing having inlet and outlet ports, the casing interior formed with a cavity, a valve holder secured within the cavity and open to one of the casing ports, the holder provided with a valve seat, a spring-closed valve for the seat located within the holder, a lever support embracing the holder and movable longitudinally of the valve axis, motion-compounding levers fulcrumed to the support with one of the levers adapted to transmit opening movement to the valve, and a thermostatic device connected to the valve casing and operatively engaging the support for moving the latter.

12. The combination of a valve casing having inlet and outlet ports, the casing interior formed with a cavity, a valve holder secured in the cavity and open to one of the casing ports, a valve seat and a spring-closed valve within the holder, a forked lever support within the casing cavity and embracing the holder and movable longitudinally of the valve axis with the support arms disposed

at opposite sides of the holder, motion-compounding levers fulcrumed to said arms with one of the levers adapted to transmit opening movement to the valve, and a thermostatic device secured to the casing and adapted to transmit movement to the lever support.

13. The combination of a valve casing having inlet and outlet ports, the casing formed with a hollow extension and with an internal cavity which communicates with said extension and with which cavity one of said ports is in communication, a holder secured within the cavity and open to the port which is in communication with said cavity, a valve seat and a spring-closed valve within the holder, the casing cavity enlarged laterally at opposite sides of the holder, a forked support movable in the cavity and casing extension with the support arms located in the lateral enlargements of the cavity, movement multiple levers fulcrumed to the support arms with one of the levers adapted to impart opening movement to the valve, a thermostatic tube connected to said casing extension, and a thermostatic rod within the tube and operatively engaging the support for transmitting movement thereto.

14. The combination of a valve casing having inlet and outlet ports, the casing interior formed with a cavity, a cup-like holder secured in the cavity and in open communication with one of the casing ports, a valve seat and a spring-closed valve within the cup, a forked support embracing said holder and movable longitudinally of the valve axis, the support formed with a hollow stem and a coiled spring located therein and bearing against said holder, movement multiple levers fulcrumed to the support arms with one of the levers adapted to transmit opening movement to the valve, and a thermostatic device in operative engagement with the stem portion of said support for moving the latter in opposition to the stem-enclosed spring.

15. The combination of a valve casing having inlet and outlet ports, one side of the casing formed with an open face, a closure for said face, the side of the casing opposite said open face formed with a hollow extension, a cup-like holder secured in the casing and at one side in open communication with one of the casing ports, a valve seat carried by the cup and facing said casing closure, a spring closed valve within the cup, a forked lever support embracing said holder and movable longitudinally of the valve axis, a thermostatic device operatively connected to the support for moving the latter, movement compounding levers fulcrumed to the support arms and located intermediate the valve seat and said casing closure with one of the levers adapted to transmit opening movement to the valve,

and a device adjustable through the casing closure and constituting an abutment for another of said levers.

16. The combination of a valve casing having inlet and outlet ports, one side of the casing formed with an open face, a closure for said face, the side of the casing opposite said open face formed with a hollow extension, a cup-like holder secured in the casing and at one side in open communication with one of the casing ports, a valve seat carried by the cup, a spring-closed valve within the cup, a lever support embracing said holder and movable longitudinally of the valve axis, a thermostatic device operatively connected to the support for moving the latter, movement compounding levers fulcrumed to the support and located intermediate the valve seat and said casing closure with one of the levers adapted to transmit opening movement to the valve, a screw device adjustable through the casing closure and adapted to form an abutment for another of said levers, and a cap rotatably embracing the closure closed face of the casing with the cap secured to said screw and constituting a hand-hold for adjusting the latter.

17. The combination of a valve casing having inlet and outlet ports, a valve seat and a valve within the casing, a thermostat, mechanism operatively connecting the thermostat and valve, adjusting means for said mechanism consisting of a stem threaded through a wall of the casing, a hand-hold forming device at the exterior of the casing and secured to the stem for adjusting

the latter, and means on the casing and said device for indicating the temperature to be maintained by the valve.

18. The combination of a valve casing having inlet and outlet ports, a valve seat and a valve within the casing, a thermostat, mechanism operatively connecting the thermostat and valve, motion-compounding levers operatively connected to the thermostat and to the valve, an adjustable abutment for the levers consisting of a stem threaded through a wall of the casing and at its inner end engaging one of said levers, a hand-hold forming device at the exterior of the casing and secured to the stem for adjusting the latter, and means on the casing and said device for indicating the temperature to be maintained by the valve.

19. The combination of a valve casing, a valve and a valve seat therein, a lever support within the casing and movable in the direction of movement of the valve, a thermostatic device for imparting movement to the support, a lever abutment within the casing and spaced from the valve, and reversely extending coacting levers fulcrumed to said support and traversing the plane of movement of the valve with one of the levers adapted to transmit movement to the latter and with another of the levers in engagement with the abutment.

In testimony whereof, I affix my signature in the presence of two witnesses.

ROBERT T. PARISEN.
